UNITED STATES PATENT OFFICE

2,328,318

HINGEDLY MOUNTED TELEPHONE
ACCESSORY SHELF

Francis Tvracky, Chicago, Ill.

Application September 16, 1941, Serial No. 411,008

2 Claims. (Cl. 211—62)

This invention relates to certain new and useful improvements in hingedly mounted telephone accessory shelves, and has among its objects to provide a hinged adjustable telephone shelf combined with a simple support for telephone directories, personal telephone address book, and paper pad for recording of notes thereon, and which hinged shelf provides a support for all of said useful telephone accessories in a convenient laterally adjustable structure of comparatively simple construction, low cost of manufacture, and which is adaptable for installation without the necessity of extensive alterations or the employment of special tools.

Another object of my invention resides in the provision of an adjustable hingedly mounted telephone shelf of the above-described character or combination which may be readily constructed of various inexpensive durable materials such as wood or metal in a structure composed of a minimum number of parts which are readily assembled with a minimum of labor into the finished structure.

A further object of my invention is found in the construction of telephone utility shelf of the above-described combination of metal parts consisting of a pair of bent metal bars and comparatively thin metal plates.

With the above and other objects in view, my invention consists in the novel combination, construction and arrangement of the parts and members shown in preferred embodiments in the attached drawing, described in the following specification and particularly pointed out in the appended claims.

In the drawing, wherein like reference numerals indicate like or corresponding parts or members:

Fig. 1 is a view in perspective of a telephone shelf embodying my invention;

Fig. 2 is a vertical section taken on line 2—2 of Fig. 1;

Fig. 3 is a modified form of my telephone shelf constructed of metal;

Fig. 4 is a cross-section taken on line 4—4 of Fig. 3;

Fig. 5 is a detail in part section showing one manner of connecting the ends of the two bent bars used in the structure of the shelf shown in Figs. 3 and 4;

Figs. 6 and 7 show respectively front elevation and plan view of the telephone shelf supported on an extended hinged bracket; and

Fig. 8 is a vertical section taken on line 8—8 of Fig. 6.

Referring particularly to Figs. 1 and 2, the hingedly supported laterally adjustable shelf 50 shown therein comprises a vertically disposed supporting wall 15 hingedly supported, as on the hinges 16, on a door jamb 17, wall or the like.

Extending laterally from the vertical supporting wall 15, and secured thereto, are three vertically spaced shelves 18, 19 and 20.

The top shelf 18, as shown in the embodiment 10 in Figs. 1 and 2, preferably does not extend outwardly as far as the intermediate and bottom shelves, respectively, 19 and 20 for the reason that this top shelf 18 functions simply as a support for the telephone instrument 21 and for the further reason that the shortening of such top shelf 18 provides a side-enclosed compartment 22 between such shelf 18 and the intermediate shelf 19 for a personal telephone address book 23 and further permits the upper outer face of the intermediate shelf 19 to be conveniently adapted for support thereon of a paper 24^a upon which notes may conveniently be recorded.

The spaced shelves 19 and 20 define the compartment 25 for the telephone directories 26.

For purposes of structural rigidity, side walls 27 and 28 are provided for the outer ends of the compartments 22 and 25.

Any suitable pad of paper may be placed upon the exposed upper face of the shelf 19, however, I have preferably shown a metallic holder for a roll of paper 27.

The roll of paper 24 is confined against displacement but free for rotation between a short upstanding wall 29 and the rear curved end 30^a of the sloping top cover plate 30 of the metallic holder. The top plate 30 is cut out, as at 30^b to pass therethrough the extended end portion 24^a of the paper cover plate 30 for writing thereon, and the end of the paper 24^a extends under an upwardly pressed-out portion 30^c which provides a cutting edge for the used paper.

The top plate 30 is formed with a downwardly bent side wall 30^d and is hinged at 31 for replacement of the paper roll 24.

Figs. 3, 4 and 5 illustrate the embodiment of my invention in a metallic shelf structure which is composed of a pair of bent bars of preferably round cross-section indicated by numeral 32. One portion of each bar 32 is bent into rectangular form to constitute a pair of spaced vertical side portions 32^a and 32^c, a bottom horizontal portion 32^b, and the top horizontal portion 32^d.

The top horizontal portion 32^d of each bar is extended beyond the end 32^e of the vertical portion 32^a and the end 32^e of the bar 32^a is secured

to the horizontal top portion 32^P as by the shouldered rivet construction illustrated in Fig. 5.

The extended top horizontal portion 32^P of each bar 32 is bent into rectangular form of comparatively small shape wherein the horizontal end portion 32^F constitutes a bottom horizontal bar portion disposed parallel to and spaced below the extended end of the top bar portion 32^P. The downwardly bent vertical portion 32^G constitutes a side bar portion which is parallel to the vertical portion 32^A.

The laterally spaced bars 32 constitute supports for the wall plate 33. This plate 33 consists of a vertical wall portion 33^A and an extended laterally disposed portion 33^B. The opposite side portions of plate 33 are bent around the bar portions 32^B and 32^C, as shown in Fig. 4.

The plate wall portion 33^A is provided with a pair of hinges 16 which are secured, as shown, to the door jamb 17. The plate platform 33^B constitutes a compartment shelf for support of telephone directories.

A top plate 34 has opposite side portions bent about the top horizontal bar portions 32^P and this plate 34 constitutes a top shelf for support thereon of a telephone instrument or note pad.

A compartment 35 for a personal telephone address book is provided by the installation of a shelf composed of plate 36 having opposite end portions bent about the horizontal bar portions 32^F. The ends of the horizontal bar portions 32^F are welded or rivet-connected to the vertical bar portions 32^A as in the manner shown in Fig. 5.

The embodiment of my invention illustrated in Figs. 6, 7 and 8 includes a novel double hinged pivotal support or arm 37 for the shelf 50 which is of similar design to that illustrated in Figs. 1 and 2.

The arm 37 is preferably disposed angularly and provided with oppositely disposed pivot posts 38 and 39. The post 38 extends downwardly into pivotal support on the bracket 40 which, as here illustrated, is secured to the leg of a desk 41. The shelf 50 is also provided with a bracket 40 which is secured to the shelf 50 in reversed position relatively to the bracket 40 on the desk 41, and the pivot post 39 extends upwardly into the bracket 40 on the shelf 50.

The double hinged arm 37 permits positioning of the shelf 50 at various angular positions relatively to the desk 41.

As above stated, the shelf illustrated in Figs. 6, 7 and 8 is similar to that shown in Figs. 1 and 2 with the exception that the holder for the roll of note paper is substantially constructed of wood and includes a side wall portion 28^A which is an extension of the side wall 28, a rear wall, 42, and an inclined wooden desk-block 43 for the extension 24^A of the paper roll which is passed on a pair of spaced retaining straps 44 of this metal.

I claim:

1. A telephone accessory device comprising a single pivotally supported vertical side wall, a horizontal top shelf, a horizontal intermediate shelf spaced below said top shelf, a horizontal bottom shelf spaced below said intermediate shelf, said intermediate and bottom shelves being wider

than said top shelf but all of said shelves being of equal length, the space between the top and intermediate shelves providing an upper compartment space, the space between the intermediate shelf and the bottom shelf providing a lower compartment space, said pivotally supported vertical side wall constituting a side closure wall for said upper and lower compartment spaces, a second vertical side wall spaced laterally from the pivotally supported side wall and extending upwardly from the top face of the intermediate shelf to said top shelf and constituting a side closure wall for said upper compartment space, a third vertical side wall spaced laterally from second vertical side wall and constituting a side closure wall for said lower compartment space, all of said shelves being fixed in stationary position relatively to said pivotally supported vertical side wall, the difference in the lengths of said top and intermediate shelves providing an elevated supporting face on said top shelf for a telephone instrument and a relatively lower supporting face on the intermediate shelf for support thereon of note paper, said housing comprising a hollow cover having an inclined top provided with a slot near the upper end thereof and a transversely disposed band near the lower end of said top, the free end of the roll of paper being extensible through said slot, over the face of said inclined top, and under said transverse band, and hinge means secured to said pivotally supported vertical side wall whereby the device is bodily movable only in a horizontal plane.

2. A telephone accessory device comprising a single pivotally supported vertical side wall, a horizontal top shelf, a horizontal intermediate shelf spaced below said top shelf, a horizontal bottom shelf spaced below said intermediate shelf, said intermediate and bottom shelves being wider than said top shelf but all of said shelves being of equal length, the space between the top and intermediate shelves providing an upper compartment space, the space between the intermediate shelf and the bottom shelf providing a lower compartment space, said pivotally supported vertical side wall constituting a side closure wall for said upper and lower compartment spaces, a second vertical side wall spaced laterally from the pivotally supported side wall and extending upwardly from the top face of the intermediate shelf to said top shelf and constituting a side closure wall for said upper compartment space, a third vertical side wall spaced laterally from second vertical side wall and constituting a side closure wall for said lower compartment space, all of said shelves being fixed in stationary position relatively to said pivotally supported vertical side wall, the difference in the lengths of said top and intermediate shelves providing an elevated supporting face on said top shelf for a telephone instrument and a relatively lower supporting face on the intermediate shelf for support thereon of note paper, and hinge means secured to said pivotally supported vertical side wall whereby the device is bodily movable only in a horizontal plane.

FRANCIS TVRZICKY.
